UNITED STATES PATENT OFFICE.

THOMAS F. MORRISSEY, OF NEWARK, NEW JERSEY.

BUTTON-FINISHING MACHINE.

SPECIFICATION forming part of Letters Patent No. 634,306, dated October 3, 1899.

Application filed September 21, 1898. Serial No. 691,516. (No model.)

To all whom it may concern:

Be it known that I, THOMAS F. MORRISSEY, a citizen of the United States, residing at Newark, in the county of Essex and State of New Jersey, have invented certain new and useful Improvements in Button-Finishing Machines; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

The objects of this invention are to facilitate the work of polishing or buffing or otherwise finishing the buttons and by applying them more quickly and regularly to the polishing-wheel to reduce the cost of manufacture, to secure a more uniform product, to dispense with the use of hand labor to a large extent, to secure the buffing effects by mechanical means only, and to secure other advantages and results, some of which may be referred to hereinafter in connection with the description of the working parts.

The invention consists in the improved button making or finishing machine and in the arrangements and combinations of parts thereof, all substantially as will be hereinafter set forth, and finally embraced in the clauses of the claim.

Referring to the accompanying drawings, in which like letters and figures of reference indicate corresponding parts in each of the several views, Figure 1 is a front elevation of the improved machine. Fig. 2 is a side elevation of the same. Fig. 3 is a front view in detail of a cam employed for operating the several levers, &c., by means of which the button to be buffed or polished is transferred from the feeding device to the polishing-wheel and then delivered to the stripping device or chute for carrying the finished button away from the machine. Fig. 4 is a section of said cam on line x , Fig. 3. Fig. 5 is a front detail elevation of the said button-chute and a releasing-fork in connection therewith. Fig. 6 is a detail plan of the said fork. Fig. 7 is a front view in detail of a certain button take-off in connection with said chute. Fig. 8 is a plan of the same. Fig. 9 is a plan of the take-off

fingers of said take-off. Fig. 10 is an edge view of the same. Fig. 11 is a plan of the chute with the take-off in position thereon. Fig. 12 is a detail front elevation, on an enlarged scale, showing certain feeding devices more clearly. Fig. 13 is a side view of the same, looking in the direction indicated by the arrow in Fig. 1. Fig. 14 is a detail view of a receiver for the partly-finished buttons having a feed-disk therein and showing the buttons in the act of being fed to the feeding device. Fig. 15 is a rear view of the same. Fig. 16 is a detail front view of a certain yielding lever arranged in the machine at the point of out-passage of the button from the said receiver to the feed device. Fig. 17 is a plan of the same. Figs. 18 and 19 are detail views of a lever or link adapted to coöperate with the parts referred to in connection with Figs. 16 and 17. Fig. 20 is another front elevation of a portion of the receiver, feed-disk, and co-operating parts stationed at the point of out-passage of the button from said receiver. Fig. 21 is a detail bottom plan of a certain slide extension. Fig. 22 is a front elevation of a hopper in connection with the feed device adapted to receive the buttons from a receiver. Fig. 23 is a side view of the same. Fig. 24 is an edge view of a certain slide adapted to be arranged in bearings at the bottom of said hopper. Fig. 25 is a detail face view of a plate adapted to be inserted in said hopper at one end thereof to regulate the size of the bottom passage therethrough. Fig. 26 is an edge view of the same and showing a spring pressing against the face thereof and serving to hold the buttons in a proper normal position as they gravitate into said hopper. Fig. 27 is another detail side view of the button-receiver and feed devices in connection therewith. Fig. 28 is a front view in detail of one set of cut-off devices for controlling the out-passage of the buttons from the receiver. Fig. 29 is a bottom or edge view of the same. Figs. 30 and 31 are views of supplemental cut-offs coöoperating with those shown in Figs. 28 and 29 for regulating and controlling the out-passage of the buttons. Fig. 32 is a front elevation of a slideway and its bearings adapted with its connections to give motion to the regulating devices above referred to and operating a certain oscillat-

ing button-carrier adapted to receive the button from the hopper of the feed devices and carry it to an oscillating chuck. Fig. 33 is a section of the same, taken on line y of Fig. 32. 5 Fig. 34 is a front view in detail of the said oscillating button-carrier. Fig. 35 is a section of the same, taken on line z , Fig. 34. Fig. 36 is a plan of the said carrier. Fig. 37 is a plan showing more in detail certain grasping-fingers on said carrier. Fig. 38 is an edge view of one of said fingers. Fig. 39 is an under side plan of a yielding back-plate upon which the front of the button rests as it is placed in position on the carrier preliminary 10 to being transferred to the chuck. Fig. 40 is a section of the same on line w' , Fig. 39. Fig. 41 is a side elevation of an oscillating chuck-carrier having the chuck and chuck-spindle arranged therein. Fig. 42 is a front view of 15 the same. Fig. 43 is a detail view of the chuck-spindle and sleeve. Fig. 44 is a central longitudinal section of the chuck. Fig. 45 is a side view of the same. Fig. 46 is a detail plan of a certain slide for operating the 20 chuck-jaws. Fig. 47 is a section of the same on line y' , Fig. 46. Fig. 48 is a detail view of the body portion of the chuck. Fig. 49 is a section of the same, taken on line z' , Fig. 48. Figs. 50 and 51 are detail views of the chuck- 25 jaws. Fig. 52 is a section of one of said jaws, taken at line x'' , Fig. 50. Fig. 53 is a plan in detail of a bracket carrying a pair of idle pulleys which are arranged pivotally to accommodate the chuck-spindle-operating belt 30 to the movements of the oscillating carrier or the oscillation of the belt-pulley on the spindle of said carrier. Fig. 54 is a side view of the same. Fig. 55 is a plan of a pair of levers for operating or controlling a certain 35 slide of the chuck, the said levers being controlled in turn by the cam of Fig. 3; and Fig. 56 is a front view of the same.

In said drawings, a , Figs. 1 and 2, indicates a suitable frame arranged on standards or 40 studs b b' . At one side of the said frame is arranged a buffing or finishing wheel c and suitable means for rotating the same, such as the belt and pulley c' c'' , Fig. 1, and at the opposite end is arranged a feeding mechanism comprising a receiver d , means for arranging the buttons in a series or succession, means for feeding them one by one to a hopper p , and an oscillating button-transferring arm or carrier f , adapted to take the button 45 from the said hopper and place it upon the chuck at the upper extremity of a second oscillatory arm g . The said second vibratory arm g comprises a lever h , fulcrumed at i upon said standard b near the lower end of 50 said standard, and a spindle s for rotating said chuck as the arm h oscillates. Said arm h is given oscillatory reciprocations by a cam j (shown in Fig. 3) and a cam-groove j' , which receives the trundle j' , formed or arranged 55 upon the rear side of the lever, as shown in Figs. 1 and 3. The lever-like reciprocating chuck-arm h is given a movement sufficient

to bring the upper end of the chuck r from a point where it receives the buttons from the carrier f to the peripheral face of the 70 buffing or polishing wheel c and from thence to a point where it enters into engagement with stripping means k for removing the said buttons from said chuck and causing them to pass down a suitable way or chute 112 to 75 a receptacle for the finished buttons.

While I have shown in the drawings a detail construction by which I accomplish the results desired, I do not wish to be understood as limiting myself thereto, for I am 80 aware that various modifications of construction may be employed without departing from the spirit or scope of the invention, and consequently I do not wish to be understood when describing the parts in detail herein-after as limiting myself by the positive expressions and descriptive terms employed excepting as the state of the art may require. With this understanding I proceed to describe in detail the peculiar arrangements of parts 85 by which I effect the automatic or purely mechanical polishing of the button.

In describing the detail construction I prefer to follow the course of the button through the machine to enable a better understanding 90 of such construction to be obtained.

The unpolished or partly-finished buttons are first inserted in large quantities in the receiver d . This receiver and the parts immediately coöperating therewith are somewhat similar in general construction to the one shown in the feeding device of the button-machine shown in my prior patent, No. 547,561, dated October 8, 1895. In my said prior patent the receiver was an open hopper. 105 In the present construction the receiver comprises a spun sheet-metal case d' , the sides of which flare toward the back of the machine and which at its rear edge is provided with a flange by means of which it is fastened by suitable screws or otherwise to a rear plate l , rigidly secured upon the arm a' of the frame of the machine. The said plate l is inclined, as in my prior construction. The forward part of the said case d' is open, 110 and the opening is closed at the lower part by a glass plate d'' and at the upper part by a hinged door d''' , the glass plate serving to permit an easy inspection of the interior of the receiver, while protecting the buttons 115 from lint, dust, &c., produced in the polishing operation, the said dust if allowed access to the buttons being detrimental to a proper feeding operation in that it tends to clog the parts and prevent the desired automatic operations. 120

At one side of the receiver d the same is open or slotted, as shown in Fig. 1, and through the slot the notched periphery of the rotary disk m projects. The said rotary disk m is 130 similar in construction to the one shown in my prior patent, it being also provided at its center with radial ribs (shown in Fig. 14) for facilitating the turning of the buttons and

causing them to properly enter the edge notches, and the said notches serving to receive the buttons, arrange them into a series, and feed them regularly and uniformly to the feeding mechanisms outside of the receiver. The buttons entering into the notches the same are carried upwardly within the receiver and thence down into the slot in said receiver, and from thence the said buttons are fed to the coöperating feeding devices.

The inclined plate *l*, upon which the notched disk *m* rotates, is provided with a raised margin *l'*, and said margin outside of the receiver-case serves to hold the buttons within the notches, and a spring guide or keeper 5, Figs. 1, 12, and 14, is arranged in front of the notches of the periphery of the disk outside of the said case, also to hold the buttons in place within said notches. The raised margin *l'* of the inclined plate at the point from which the buttons are to be fed therefrom is provided with an opening 6, as shown in Fig. 12, through which the buttons pass out automatically by gravity upon the inclined way or passage 7, formed on the upper face of a bracket 8, when said way is not obstructed by another button lying on said way or by a cut-off gate 9, lying at said opening, or by an antijamming stop 44, hereinafter to be described.

In my prior device the out-passage opening 6 for the buttons was formed between end walls of the raised rim *l'* of the inclined plate. At this opening was arranged a spring to prevent jamming; but notwithstanding this spring the buttons when not properly fed were apt to catch or jam, the limited elasticity of the spring being insufficient to prevent the trouble and in some cases occasioning a damage to the button.

To more perfectly avoid the possibility of injury to the button, I have in the present construction arranged at one side of the button-egress opening 6 of the receiver a movable piece 12, which supplements the raised margin, and being hinged or pivoted at 13 to the end 110 of the raised margin *l'* extends in the curved line of the said margin to a point about midway of the opening, where at its free end it receives a second hinged piece 14, which latter is raised above and away from the plane of the rib or raised margin *l'* and supplemental piece 12 to permit of the passage of the button beneath. The hinged piece 14 is pivoted to the bracket 8 at 15, Fig. 20, outside of the upper end of the margin *l'*, and at its opposite or lower end it is loosely linked to the piece 12, a suitable slot 160 being provided in one of said pieces to permit of the desired knuckle action. The hinge-piece pin 18 works in said slot and holds the pieces together at their free ends.

The buttons are permitted to pass between the upper end of the margin *l'* and the end 65 of the supplemental piece to enter into engagement with a pocket-stop for preventing a direct passage of the button into the hopper

beneath; but should the button because of some abnormal movement or other condition fail to pass through said opening 6 and tend to become jammed in said opening to the injury of the button the abutting free end of the supplemental piece, being only held in normal position by a spring 20, gives under the pressure of the button to prevent injury and sets a train of devices into operation by which the button is immediately returned into its notch in the periphery of the disk *d*.

Under pressure of the button, as described, the pieces are forced outward and operate a cam-arm 21, which, pivoted upon the hinge-pin 18 and extending through the slot 16, Fig. 17, receives the spring 20. The said cam-arm when pressed, when the pieces 12 14 are pressed out by the button, is caused to engage a slide or pressure-piece 19 with an elastic pressure due to the spring 20, and this pressure is sufficient to overcome the pressure of the spring 49 of the pressure-piece 90 and effect a lengthwise movement of said pressure-piece at its slotted end. (Shown in Figs. 20 and 28.) Said pressure-piece at its end opposite that engaged by the cam-arm is pivoted upon the short arm 45 of the lever-like stop or cut-off arm 44 and causes said arm 44 to turn on its fulcrum pin 40, which is preferably removable, and throw its free longer arm downward into the opening 6 to stop the progress of the button out through said opening, holding said button so that the continued movement of the disk and the bearing at the end of the piece 12 throws said button back into its notch in the disk before injury by jamming is received. Under normal conditions, however, the button is permitted to pass through the opening 6 onto the slideway of the bracket 7, attached to the receiver; but here its downward gravitation over the inclined slideway is almost immediately stopped by another cut-off or stay 38, hereinafter more fully described.

To secure a more perfect control of the feeding of the button and to permit of a normal out-passage of the said button from the receiver only when the way is prepared for the same, I provide button stops, gates, or cut-offs, which are controlled by the slide 19 and cam part 21. The first cut-off of the series is the gate 9. This comprises a hooked piece 115 which is pivoted at the back of the receiver-plate, as indicated in Figs. 14 and 15. The said gate 9 receives its motion from the upward extension 23 of the slide 22, the said slide having bearings in the bracket 8 and 120 engaging the shoulder or bearing 24 of the said gate and pressing the hooked end inward toward the opening 6, the extremity closing the same, so as to prevent the out-passage of the button. The said slide 22 and its extension 23 are reciprocated by the arm 27, Figs. 1, 12, and 15, pivotally fastened upon a second slide 28, arranged in bearings in the frame *a*, and this slide in turn is reciprocated by a le-

ver 29, fulcrumed at 281 on the bed or frame *a* and extending downward to the cam *j*, where the lever-arm of said lever engages a cam projection 291, Fig. 1, to receive its reciprocating movement in one direction. To receive the return movement, the lever 29 is in connection with a compound lever 31, the members of which are hinged together at 32, the said compound lever being pivoted to the lever 29 at 33, and upon suitable fulcrum 34, near the foot of the standard *b*. The lever 31 carries the trundle 35, which engages a cam-surface 36 upon the cam *j*, by which means or by any other means desired I secure an oscillation of the lever 29 and reciprocating sliding action of the slide 28 and a corresponding reciprocation of the arm 27 and slide 22, by which the gate 9 is alternately opened and closed, the parts being timed to prevent a second button issuing from the receiver while a first one is on the slideway.

When the gate 9 is closed by the pressure of the extension 23 against it, it is done so against the pressure of a spring 37, Figs. 14 and 15, which latter opens said gate 9 a limited distance automatically when the pressure of the extension 23 is removed. The opening of the gate 9 permits an out-passage by gravity of the button from the notch in the disk 30 then coinciding with the opening 6, the button passing out through said opening 6 upon the inclined way 7 of the bracket 8.

The bracket 8 is provided with lugs or bearings 39 39, Fig. 12, which are perforated to receive a removable pin 40, upon which latter, between said lugs, is pivoted the said cut-off or stop device 38. The body of said cut-off device consists of an irregular piece of metal having a fulcrumal bearing to receive the pin 40 and fit between the lugs 39. Said body is bent at one end to give to said body a crank shape, the bent extension 41 serving to receive and be operated by a bearing 42, Fig. 20, of the arm or extension 23 of the slide 22 when the said extension closes against the gate 9, the bearings 23 and 42 engaging, respectively, the gate 9 and the extension 41 simultaneously, or approximately so, thus closing the opening 6 to prevent the out-passage of a button and raising the body 38 of the cut-off from the face of the slideway 7 to permit the button lying back of the said cut-off body to drop into the hopper *p*. At the back of the said cut-off body 38 the same is provided with a suitable downward projection or formation 3811, Figs. 28 and 29, which serves as a stop or pocket for the downwardly-moving button, and is also provided with an adjusting-screw 43 for regulating the distance of pivotal movement toward the slideway 7 of the bracket. The body 38 of the cut-off not only carries the stop projection 3811, but provides the bearings 47 for the pressure-piece or slide 19 before referred to in connection with the device for throwing the button back into the notch of the disk should it catch or be improperly fed to the cut-off body 38. Upon

the engagement of the bearing 42 with the arm 41 of the cut-off body 38 the said cut-off body 38 is raised from the way 7 and the button beneath is allowed to drop or slide down said way into the hopper *p*, where it is turned to lie substantially at right angles to its former position by striking the inclined wall of the hopper as it drops. The bottom of said hopper is slotted to permit the out-passage of the button, the bottom opening being controlled by a slide-valve 50, which is kept normally closed by a spring 51, Fig. 12, the said slide-valve working in a suitable slideway or bracket 52, attached to or formed on the hopper. The opening or passage at the bottom of the hopper is made large or small to suit the differently-sized buttons by means of an adjustable plate 54, arranged within the hopper and controlled by suitable adjusting-screws 55 56. At its forward end the said slide or valve 50 is provided with a downward projection 53, adapted to be engaged by an oscillating button-carrier *f*. Said button-carrier *f* is adapted to oscillate between the hopper *p* and the button-chuck *r* when the latter is in its button-receiving position, so as to receive the button from said hopper and carry it to said chuck, by which latter the said button is presented to the polishing-wheel *c*. Said carrier *f* is operated by the slide 28, which latter is provided with a rack 57 to engage a pinion 59, having a pivotal shaft or hub 60, with bearings in the frame 100 of the machine. Said shaft or hub 60 moves with said pinion and has the body of the carrier fixed thereon, so that said pinion, hub or shaft, and carrier are adapted to oscillate together as the slide 28 is reciprocated by the lever 29, as above described. Said carrier is preferably adjustably fastened upon said shaft or hub 60. A set-screw 61 fastens the carrier to the hub and permits the desired adjustment. Said carrier *f* comprises a body-plate 62, to the under side of which is attached or formed a lug 63, providing bearings for the hub and set-screw 61, which lug is formed at the lower end of the said body-plate 62. At the opposite free end of said body-plate 62 means are provided to receive the button as it drops from the hopper and to hold said button firmly in place at said free end while the carrier makes an oscillation or turns over upon the chuck, the operating parts being timed in their movements, so that the button will be placed in position at the said free end of the chuck by said carrier, the button being forwarded by said chuck to the periphery or polishing-surface, as before described.

Upon the upper face of the reciprocating body-plate 62 are pivoted upon the pin or screw 631 the shear-like grasping-fingers 64 65, having at their free ends curved flanges 66 65, which together form a pocket or receptacle for the button as it slides from the hopper over the body-plate of the carrier, the upper ends of said flanges being separate, as in

Figs. 13 and 37, so that when the fingers 65 are spread a passage of sufficient width for the button will be formed, the lower end of the curved flanges serving as stops, preventing further passage, as will be understood. The said flanges are undercut or inwardly shouldered, as at 651 in Fig. 35, to hold the button in place between the flanges when the fingers are closed and are more or less funnel-shaped or flaring on their concave sides to serve as guides for the chuck to bring the latter into a proper relation to the button when the carrier is turned down upon said chuck. Said flanges are preferably removable from the body of the fingers to permit of an interchange of flanges to suit different sizes of buttons.

The fingers 64 are normally held together by a spring 66 and are spread apart so as to permit the entrance of the button from the hopper by a lever 67, Figs. 12, 13, and 34, which is fulcrumed at 68 upon the under side of the body-plate 62 and passing at one end through a slot in the plate 62 is made at its extremity wedge shape, and is thus adapted to enter between the said fingers 64 to spread the same apart. Said lever 67 is operated by engaging at its opposite end a trundle 69, arranged on a short stud in connection with the slide 28. As the said slide moves forward with the trundle it turns the pinion 59 in the reverse direction and causes an engagement of the lower arm 671, Fig. 12, of the lever with the said trundle 69 and a movement of the carrier toward the hopper and at the end of the movement an engagement of the carrier-plate with the projection 53 of the hopper slide, gate, or valve 50, throwing the latter open simultaneously with the opening of the flanges 65 to permit a passage of the button therebetween. When the finger-flanges are closed against the button, the latter is pressed a little forward against the shoulders 651 by a pressure-plate 70, Figs. 35, 39, and 40.

At a point near the free end of the carrier in coincidence with the chamber or aperture between the flanges 65 I have formed an opening for the pressure-plate above referred to. Behind the plate 62 at said opening I have arranged a short cylindrical pocket 71, Figs. 12, 34, and 35, in which is arranged a spring 72, Fig. 35. The pressure-plate 70 is provided at its back with another cylinder 73, which works telescopically in said cylinder 71, the spring 72 lying at one end within said cylinder and at the other against the bottom of the pocket 71. At the center of said pressure-plate at the back and within said cylinder 73 is formed a shank 74, which extends back through a perforation in the bottom or end of said cylinder 71 and thereat receives a crank-lever 75, fulcrumed upon a stud 76, Figs. 34 and 36, one arm of said lever being loosely pivoted to the outer end of the shank 74 and the other arm providing a bearing for the long spring 77, which last is adapted to engage a bearing 78, Fig. 12, upon the frame of the

machine as the button-carrier approaches in its return movements the hopper *p*. The said spring 77 is of sufficient strength to counteract the power of the spring 72, and is thus adapted to press the pressure-plate 70 back to a position flush with the face of the body-plate 62 as the button grasping or holding fingers 64 are spread apart by action of the lever 67. The button being released by the opening of the slide 50 gravitates from the hopper onto the plate 62 and enters between the grasping-fingers 64 and over the plate 70, the edges of the button entering beneath the undercut shoulders formed at the inner edges of the flanges 65. The button having entered between the fingers by gravity, the grasping-fingers first close upon the edges of the button and start with the carrier in its oscillation toward the chuck. Almost immediately the spring 77 passes from engagement with the bearing 78 and permits the spring 72 to force the pressure-plate 70 forward against the face of the button, clamping the latter against the sides of the flanges. The carrier continues its movement until the button is brought into contact with the chuck, where said button is caught and held by said chuck in a manner which I will now proceed to describe.

Upon one of the studs or standards *b*, near the base thereof, is fulcrumed the oscillating chuck-carrier *h*. This is given its oscillatory movement, by which the chuck is caused to travel the face of the polishing-wheel, by the cam *j*, which last is provided with a cam-groove 79, Fig. 1, the said chuck-carrier being provided with a suitable pivot *j'*, upon which is arranged a trundle 80, which latter works in said cam-groove, as will be understood. The said lever-like chuck-carrier is provided at its upper free end with bearings $h^3 h^4 h^5 h^6 h^7$ for a spindle 81, its sleeve 82, and a spindle-worker 83 for giving longitudinal movement to the spindle, as shown more clearly in Figs. 41 and 42. Said sleeve 82 carries the pulley 84, by means of which said sleeve is given its rotary movement. Within said sleeve it is provided with a suitable key, feather, or spline 85, which works in a longitudinal groove 86, formed in said spindle. The said spindle is thus caused to rotate with the sleeve and at the same time is permitted a longitudinal movement independent of said sleeve. The lower end of the spindle 81 is loosely coupled to the non-rotary spindle-worker 83, and the latter is given at suitable times the desired longitudinal movement by means of a system of levers, hereinafter described, operated upon by the cam *j* or by any other suitable means. At the upper end of the said spindle 81 is arranged the check *r*, which latter is thus given both an oscillatory movement, by means of which it is caused to traverse the space between the carrier *f* and stripping devices, a rotary movement, whereby the button is rapidly turned as it traverses the polishing-surface of the wheel

c, and a longitudinal movement, by means of which the said chuck is raised and lowered toward and from said wheel after having received the button from the oscillating carrier.

- 5 The said chuck is shown more clearly in detail in Figs. 41 to 52. The upper end of the sleeve 82 is provided with a flange or bearing 87, and the upper end of the spindle 81 is threaded, as at 88. Upon said upper end of 10 the spindle is screwed the body 89 of the chuck, the latter being provided with suitable female threads 891 to receive the same. Around said body portion of the chuck is arranged a sliding collar 90, which has a limited sliding movement. Said sliding collar 90 is provided with a key 901, which works with in a transverse slot or groove 892, Figs. 48 and 49, formed in the chuck-body, by means of which key said collar is prevented from 15 turning on said chuck-body. Said collar is normally held at its upper limit of movement on said body by a spring 91.

Within the slot 892 is arranged a sliding block 92, which is suitably pinned to the 20 sleeve 90 by the key 901, so as to slide therewith. Said block 92 is centrally apertured, the aperture 93, Fig. 47, having rounded or inclined side walls and opening at the upper end of the block and receiving a pair of cross- 25 ing or shear-like levers 94 and 95, Fig. 44, which are pivoted or fulcrumed together at 96 and at their lower extremities are arranged within said aperture 93. The upper opposite ends of said shear-like levers are 30 provided with the pintles 97, adapted to enter within the holes or eyes of the button when nearest one another. Between the lower ends of said levers I interpose a spring 98, so that said lower ends or arms have a normal tendency to be spread apart and the upper ends closed together. Thus when the collar 90 is lowered by means hereinafter described the 35 said levers 94 95 will be spread apart at their lower ends by the spring 98 and the upper 40 pintles will be brought toward one another to enter the buttonholes, and when said collar 90 is relieved of downward pressure and the spring 91 is free to press the same upward the opposite bearings 930, Fig. 47, of the block 45 92 will engage the roundings or inclines 99 99 of the levers and press the lower ends thereof together against the power of the spring 98, so that the pintles 97 will be thrown apart 50 against the walls of the buttonholes to clamp 55 the button in position upon said pintles.

The collar 90 is pressed down so as to receive the button by a compound lever 100, Fig. 1, which is fulcrumed at 101 and 102 and has its members pivoted together at 103. 60 Said lever is operated by the cam-wheel *j*, the cam grooves or projections of which are timed to cause the forked upper end 104 of the lever, as indicated in Figs. 55 and 56, to engage the collar to press the same downward 65 against the spring 91 when the oscillating button-carrier *f* is in position to receive the button from the feeding devices.

The rotation of the chuck while the latter is in engagement with the button-carrier *f* causes the pintles, closed toward one another, 70 as described, to enter the buttonholes with facility. Upon the button passing upon said pintles of the chuck from the carrier *f* the button-carrying lever passes from engagement with said chuck, and the forked lever 75 then moves from engagement with the collar 90, and immediately the spring 91 causes the pintles to lock said button in position upon the chuck as it passes toward the polishing-wheel. To move the chuck longitudinally or 80 lengthwise of its axis of rotation, so that the button is raised at one end of the oscillation to the polishing-wheel and lowered when near the button-carrier *f*, I employ means for operating the spindle-worker 83, comprising an 85 adjustable lever 105, Figs. 1, 41, and 42, which is fulcrumed upon a shaft 106, having bearings in an arm or bracket 107 at or near the bearing *h*, formed or fixed upon the arm or lever *h*. Said lever 105 is in turn operated by cam projections upon the cam-wheel *j*. The said lever 105 is linked at 125 to the spindle-worker 83, so that as the lever turns upward on its fulcrum the worker and spindle are raised with it. The arm 108 of said lever 105 serves to raise the 95 spindle and the chuck thereon upward in a position to receive the button, and the arm 109 serves to raise the spindle to bring the chuck into engagement with the polishing-wheel. Said arms are provided with suitable 100 wheels to engage cam-surfaces therefor on the cam *j*, said cam-surfaces being suitably formed to secure the desired results. After having been raised by the means described and after having traversed the periphery of 105 the polishing-wheel the chuck continues its course away from the feed mechanism a limited distance into engagement with stripping means for removing the button from said chuck. The take-off devices or stripping 110 means are shown in detail in Figs. 1 and 5 to 11, where 111 indicates a fixed fork attached to the chute 112, which serves to receive the sliding collar and press the said collar downward as said collar engages the inclined or 115 curved bearings 113 of said fork near the end of oscillation. As the said collar enters into engagement with the said fork the chuck, where it is provided with the pintles, passes into engagement with a pair of spring-actuated stripping-fingers 114 114, Figs. 9 and 10, which enter beneath the button and force the same free therefrom, so that the said button is caused to slide into the chute, from whence it is directed to a suitable receptacle below. 120 Said stripping-fingers 114 are held together in proper relation to receive the chuck and button by a spring 115.

A suitable guard 116 is provided to prevent the button from being thrown from the chute 130 when released from the chuck.

To permit a free oscillation of the chuck carrier-arm when transmitting rotary motion to the chuck-spindle, I have provided a pair

of idle pulleys 117, as shown in detail in Figs. 53 and 54, which serve in connection with the belt which actuates the pulley 84. Said pulleys are pivoted, as at 118, upon a slide 119, arranged in a suitable slideway 120 of a bracket 121. As the oscillating chuck-carrier moves backward and forward, as above described, the slide 119 correspondingly slides in its ways, the spring 122 holding said slide in proper relative position and maintaining a uniform or approximately uniform tension upon the belt. By pivoting the pulley-carriers 123 said pulleys 117 are permitted to oscillate in correspondence with the oscillation of the chuck-carrier and the pulley thereon, all as will be understood.

The movements of the chuck carrier-arm *h* are cushioned by a spring 124. The lever 105 of said arm *h* is adjusted by means of an adjusting-screw 126, which is threaded and adapted to engage the cogged extremity of said arm 105, so that said arm 105 may be raised or lowered a greater or less degree, so as to bring the chucks in their operations nearer to or farther from the operating-wheel, the said adjusting-screw thus being adapted to bring the said chuck up to the face of the polishing-wheel as the latter wears away.

Having thus described the invention, what I claim as new is—

1. In a button-machine, the combination with the buffing-wheel *c*, and means for operating the same, of an oscillating button-holding chuck adapted to present the button to the said wheel, means for oscillating said chuck and means for feeding the buttons to said chuck and for stripping the buttons therefrom at the end of each oscillation, substantially as set forth.

2. In a button-machine, the combination with the finishing-wheel, and means for operating the same, of an oscillating button-holding chuck adapted to move back and forth across the periphery of said wheel, means for oscillating said chuck, and means for automatically feeding said chuck with buttons and removing the same therefrom, substantially as set forth.

3. In a button-machine, the combination with the frame *a*, having at one side a buffing or finishing wheel and means to operate the same, of feeding devices arranged at the opposite end or side of the frame, an oscillating button-transferring arm adapted to take the buttons one by one from the feed devices and convey them to the chuck, an oscillating chuck adapted to take the buttons from said transferring device and carry them into contact with said wheel and operating means, all substantially as set forth.

4. In a button-making machine, the combination with a frame and finishing-wheel, of a button-receiver, having means therein for arranging the buttons into a series or regular succession, means for limiting the free out-passage of the buttons from said receiver, a hopper, an arm taking the buttons from said

hopper and transferring them to a chuck, and a rotary chuck movable from said transferring means to said wheel, and means for operating said parts, substantially as set forth.

5. In a button-making machine, the combination with the frame and finishing device, of feeding devices and a rotary and oscillating button-carrying chuck, and means for operating said parts, substantially as set forth.

6. In a button-making machine, the combination with a wheel *c*, of a receiver *d*, means for feeding the buttons from said receiver, means arranged in said receiver for arranging the buttons into regular series or succession, a reciprocating and rotating chuck, means for reciprocating and means for rotating said chuck, all substantially as set forth.

7. In a button-machine, the combination with a wheel *c*, of a receiver, means for feeding the buttons therefrom to a chuck, said chuck and means for reciprocating said chuck and for turning said chuck as it is presented to said wheel, stripping means and a chute, disposed in the machine at a point at the opposite side of the wheel from said receiver, substantially as set forth.

8. In a button-machine, the combination with the receiver containing a rotary disk 95 and having a side opening 6, for the button, of a pivotal piece 12, forming one of the end walls of said opening, and means for holding the free end of said piece in normal position, means for transferring the button to the finishing-wheel and operating means, substantially as set forth.

9. In a button-machine, the combination with the receiver, having a marginal rib and containing a rotary disk and having an opening 6, in said rib for the button, of a pivotal piece 12, supplementing said marginal rib and held with an elastic pressure in normal position in the line of said rib, piece-holding means and operating means, substantially as set forth.

10. In a button-machine, the combination with the buffing or polishing wheel, of button feeding and stripping means disposed at opposite sides of the said wheel, and an oscillating and rotary chuck reciprocating between said feeding and stripping means and adapted to carry the button across the face of said wheel and turn said button in its passage, and operating means for said parts, substantially as set forth.

11. In a button-machine, the combination with the frame, of a buffing or polishing wheel, and means for rotating the same, a button-receiving chuck adapted to convey the button to said wheel, and a feed mechanism comprising a button-receiver *d*, and means for arranging said buttons into a series and feeding them one by one into a hopper *p*, said hopper and means for transferring said buttons to the chuck, and operating means, all said parts being arranged and operating, substantially as set forth.

12. In a button-machine, the combination

with the frame, of a buffing or polishing wheel, and means for rotating the same, a button-receiving chuck arranged on a spindle arranged on an oscillating arm and adapted to 5 convey the button to the polishing-wheel, and means for oscillating said arm and rotating said spindle, substantially as set forth.

13. In a button-machine, the carrier, comprising a body-plate, grasping-fingers 64, 64, 10 adapted to grasp the button and a lever fulcrumed upon said body-plate and at one end entering between said fingers and adapted to spread said fingers to release the button, and means for operating said parts, substantially 15 as set forth.

14. In a button-machine, the carrier, comprising a body-plate, button-grasping fingers pivoted upon one side of said plate, a lever fulcrumed upon the opposite side of said plate 20 and at one end entering through said plate between said fingers to spread the same, and means for operating said parts, substantially as set forth.

15. In a button-machine, the button-carrier, comprising a pivoted body-plate, means for oscillating said plate, pivotal grasping-fingers, means for closing the fingers toward the button, means for spreading said fingers, and a pressure-plate for forcing the button 30 into fixed relation to the grasping-fingers, and means for operating the pressure-plate, substantially as set forth.

16. In a button-machine, the button-carrier comprising a pivoted body-plate, means 35 for reciprocating said plate, grasping-fingers, means for operating the same, a pressure-plate stationed at the free ends of said fingers and movable in a direction at right angles to the plane of movement of said grasping-fingers and means for operating said pressure-plate to effect a rigid holding of said button between said fingers, substantially as set forth.

17. In a button-machine, the button-carrier comprising a pivotal body-plate, means 45 for reciprocating said plate, and pivotal fingers adapted to receive the button therebetween, a spring for closing said fingers and means for opening said fingers against the 50 power of the spring, substantially as set forth.

18. In a button-machine, the combination with the body-plate of the carrier, of pivotal fingers pivoted at one end to said plate and at the opposite end having curved flanges to 55 receive the button therebetween, a pressure-plate arranged on said body-plate at said free end, a spring for pressing said button into engagement with said curved flanges, and means for operating said pressure-plate against the 60 power of said spring, substantially as set forth.

19. In a button-machine, the combination with the button-carrier body-plate having a cylinder 71, and means for operating the said plate, of pivoted fingers, means for opening 65 and closing the same, a pressure-plate having a shank 74, arranged in said cylinder, a lever 75, having a spring-arm 77, and a bearing for

said spring-arm, all said parts being arranged and combined, substantially as set forth.

20. In a button-machine, the combination 70 with the reciprocating button-carrier body-plate, having a cylinder 71, at its free end, pivotal bearings at its opposite end, and an intermediate stud, fingers pivoted on said plate, a lever fulcrumed on said plate and 75 having an arm adapted to separate said fingers, a spring adapted to close said fingers toward one another, a pressure-plate disposed near the free ends of said fingers and having a shank extending into said cylinder, a lever 80 fulcrumed on said stud and connected to said shank, and means for operating said parts, substantially as set forth.

21. In a button-machine, a button-carrier having separable fingers and a pressure-plate 85 movable at right angles to the plane of movement of said fingers and a spring, causing said plate to press the edges of the button against said fingers with a resilient pressure, substantially as set forth.

22. In a button-machine, the combination with the frame, of a buffing or polishing wheel and means for rotating the same, a button-receiving chuck adapted to convey the button from a carrier to said wheel, means for 95 rotating said chuck, a reciprocating carrier having separable fingers adapted to grasp the button upon receiving the same from the feed mechanism, means for operating said carrier reciprocatingly and causing it to deliver the button to said chuck, means for operating said carrier and opening and closing said fingers, means for stripping said button from said chuck and means for feeding the button to the carrier, substantially as set 105 forth.

23. In a button-machine, the combination with the frame, of a buffing or polishing wheel and means for rotating the same, a button-chuck and means for rotating the same and 110 causing it to traverse the periphery of the buffing or polishing wheel, a reciprocating button-carrier having grasping-fingers and a lever for opening said fingers, means for reciprocating said carrier and means for operating said lever to open said fingers, and means for feeding the button to said carrier, substantially as set forth.

24. In a button-machine, the combination 115 with the frame, the buffing-wheel and rotating and oscillating chuck and means for operating said parts, of a pivotal carrier adapted to grasp the button from the feed devices, a rack and pinion, the latter connected with said carrier, and means for operating said 125 rack, substantially as set forth.

25. In a button-machine, the combination with the frame, the buffing-wheel and the rotating and oscillating chuck and means for operating said parts, of a carrier comprising 130 a plate having a pinion in connection therewith and having grasping-fingers and a pressure-plate and springs normally tending to cause said parts to grasp the button with re-

5 silent pressure, means for releasing the button from said fingers, a pinion connected with said plate, a rack sliding on said frame and meshing with said pinion, means for operating said rack and means for feeding the button to said carrier, substantially as set forth.

10 26. In combination with the rotating and oscillating chuck and means for operating the same, an oscillating carrier having grasping-fingers between which the button is adapted to slide from the feed devices, the said carrier being adapted to assume an inclined position preparatory to receiving the button and timed in its relation to the chuck to transfer said 15 button to said chuck prior to the passage of the latter across the periphery of the wheel, means for operating said parts, said feed devices, and means for operating said carrier, fingers and feed devices, substantially as set 20 forth.

25 27. In combination, in a button-machine, with the rotary and oscillating chuck and means for operating the same, an oscillating carrier having a body-plate arranged at one end upon a fulcrum shaft in connection with a pinion, a rack for operating said pinion and body-plate and means for operating said rack, the free end of said carrier body-plate having a spring-actuated pressure-plate, 30 means for forcing said pressure-plate toward the plane of the body-plate when said carrier is in its button-receiving position, fingers and means for opening the fingers to receive the button therebetween as it passes onto said 35 pressure-plate, means adapted to cause said fingers and pressure-plate to hold the button firmly as it passes to the chuck and thereat to release said button, substantially as set forth.

40 28. In a button-machine, the combination with the rotating chuck and means for operating the same, of an oscillating button-carrier having a funnel-shaped receptacle to receive the free end of the chuck and guide the 45 button of the carrier in proper relation to said chuck to effect a proper transfer, substantially as set forth.

50 29. In a button-machine, the combination with a rotating and oscillating chuck and means for operating the same, of an oscillating button-carrier having at its free end a socket or receptacle for the button and end of the chuck, whereby the button-carrying carrier is guided into proper transferring relation to said chuck, and carrier-operating means, substantially as set forth.

55 30. In a button-machine, the combination with a rotating and oscillating chuck and means for operating the same, of an oscillating button-carrier having a funnel-shaped receptacle for the chuck at its free end and carrier-operating means, substantially as set forth.

60 31. In a button-machine, the combination with a rotating and oscillating chuck having pintles 97, movable toward and from one another and means for operating said chuck

and pintles, of a button-carrier having fingers movable toward, and from, one another, said carrier being adapted to place the button in 70 position on said chuck to occasion an entrance of said pintles into the holes of the button, the pintles and fingers operating means being timed in their movements to effect an opening of the fingers when the pintles enter into 75 holding relation to the button, substantially as set forth.

32. In a button-machine, the combination with the rotating and oscillating chuck having pintles at the end to enter the holes of the 80 button, said pintles being movable toward and from one another from a position to enter the buttonholes to a binding or holding relation to the button and a carrier adapted to transfer the button to said chuck and deposit 85 the same in position to receive said pintles, and means for operating said parts, substantially as set forth.

33. In a button-machine, the combination with the rotating and oscillating chuck having 90 pintles at the end to enter the holes of the buttons, said pintles being movable toward and from one another, and an oscillating carrier timed in its movements to rest down upon the chuck at one end of a stroke or oscillation 95 of the latter and deposit the carried button upon said pintles, and means for operating said parts, substantially as set forth.

34. In a button-machine, the combination with the rotary and oscillating carrier and 100 means for rotating and oscillating the same, of a chuck comprising a slotted body, a collar sliding longitudinally on said chuck-body, a sliding block arranged in the slot of said body portion and moving with said collar, 105 levers having pintles and springs adapted to effect a holding engagement of the pintles with the button, and means for operating said parts, substantially as set forth.

35. In a button-machine, the combination 110 with the carrier and means for oscillating the same, of a chuck comprising a body, a collar sliding thereon longitudinally, a pair of button-holding levers, a heavy spring for forcing said levers into button-holding relation to the 115 chuck and a light spring for releasing said levers from button-holding relation when relieved from the exerted power of the heavy spring, and operating means, all arranged and operating, substantially as set forth. 120

36. In a button-machine, the combination with the reciprocating button-carrier body-plate, of shear-like fingers 64, 64, each having a curved flange and together forming a funnel-shaped guiding-receptacle for the chuck, 125 substantially as set forth.

37. In a button-machine, the combination with the button-carrier body-plate, of shear-like fingers 64, 64, with separable curved flanges, a spring normally holding said fingers together to hold the button in its bearings, a lever 67, for opening or spreading said fingers, and means for operating said parts, substantially as set forth. 130

38. In a button-machine, the combination with the button-carrier body-plate and means for oscillating the same, of shear-like fingers 64, 64, pivoted upon said body-plate, and having button-receiving bearings and a chuck-guide, of a lever 67, wedge-shaped at one end and adapted to enter between said fingers to spread or separate the same and lever-operating means, substantially as set forth. 70
39. In a button-machine, the combination with rotary and oscillating chuck and means for operating the same, said chuck having means for holding the button and means for operating said holding means, of an oscillating button-carrier having a pair of pivoted fingers having at contiguous free ends curved chuck-guides together forming a funnel-shaped receptacle, a lever 67, wedge-shaped at one end for spreading said fingers and means for operating said button-carrier and lever, substantially as set forth. 75
40. In a button-machine, the combination with the frame, a slide having a trundle 69, and means for operating said slide, a rotary and oscillating chuck and means for operating the same, an oscillating button-carrier having pivoted fingers adapted to grasp the button therebetween, and a lever having one end adapted to enter between said fingers to spread the same and at its opposite end adapted to engage the said trundle, substantially as set forth. 80
41. In a button-machine, the combination with the oscillating body-plate of the carrier and pivoted fingers thereon and means for operating said parts, of curved flanges on their concave sides flaring to form guides for the chuck and having overhanging walls beneath which the edges of the button may be caught and held, and means for operating said parts, substantially as set forth. 85
42. In a button-machine, the combination with the oscillating button-carrier, feed devices, polishing or finishing wheel and stripping means, of a chuck-carrier h , a cam for oscillating the same, a spindle arranged on said carrier, its sleeve 82, and means for longitudinally operating the same, a pulley 84, secured to said sleeve, means for rotating the same, and a chuck attached to said spindle and adapted to receive the button, substantially as set forth. 90
43. In a button-machine, the combination with the oscillating button-carrier, having an arm or bracket 107, feed devices, polishing or finishing wheel and stripping means, of a chuck-carrier h , and means for oscillating the same, a spindle arranged in bearings on said carrier and means for rotating said spindle, the spindle-worker 83, a lever 105, linked to said spindle-worker and a cam for operating said lever and giving longitudinal movement to the spindle and chuck, substantially as set forth. 95
44. In a button-machine, the combination with the button polishing or finishing wheel and means for operating the same, an oscillating chuck-carrier, a spindle and chuck carried by said spindle, means for oscillating the chuck-carrier, means for rotating the spindle and means for moving the chuck lengthwise of the spindle to cause an engagement of the chuck and polishing-wheel while the said chuck is rotating and oscillating, substantially as set forth. 100
45. In a button-machine, the combination with a wheel and feed devices, of a rotating, oscillating and longitudinally-movable chuck, and means for operating the same, substantially as set forth. 105
46. In a button-machine, the combination with a wheel, and feed devices, of a rotating, oscillating and longitudinally-movable chuck having movable pintles to receive the buttons and hold the same while being engaged by said wheel, and means for operating said parts, substantially as set forth. 110
47. In a button-machine, the combination with the wheel, oscillating carrier, feed device and stripping means, and means for operating said parts, of an oscillating, rotary and longitudinally-movable chuck and means for operating said chuck, said chuck and co-operating parts being timed in their movements to transfer the buttons, one by one, from the carrier to the chuck and carry the same across the periphery of the wheel while turning said button and afterward deliver the button to the stripping means, substantially as set forth. 115
48. In a button-machine, an oscillating chuck and an oscillating button-carrier meeting or engaging one another at the ends of their approaching movements, the chuck being provided with means to grasp the button from the carrier, and operating means, substantially as set forth. 120
49. In a button-machine, the combination with a wheel and an oscillating button-carrier having means for alternately grasping and releasing the button, of a rotary and oscillating chuck engaging said carrier when said oscillating parts engage one another at the ends of their approaching movements, said chuck having means to hold the button when the latter is released by the carrier, and means for operating said parts, substantially as set forth. 125
50. In a button-machine, the combination with the frame and button polishing or finishing devices and means for operating the same, of a receiver having a rotary notched disk and inclined plate with raised margin and slot or opening 6, therein and a bracket extending out from said plate at said opening, a supplemental piece 12, pivoted at one end of the raised margin, a co-operating hinged piece extending over the opening between the free end of said piece 12, and the opposite end of the raised margin, said co-operating piece having a cam for operating a slide or pressure rod, said slide 19, and a crank-lever one arm of which is pivoted upon said slide and the other adapted to enter the button. 130

passage of the opening 6, to stop progress of said button through said opening before said button arrives at a position for jamming, substantially as set forth.

5 51. In a button-machine, the combination with the frame, button-carrying devices and means for operating said devices, of a button-receiver having a feeding disk and plate with an opening or passage for the buttons at the 10 margin, a supplemental marginal piece 12, adapted to be engaged by the button and moved thereby and a button stop-arm in train with said supplemental marginal piece and receiving its motion directly therefrom through 15 the train of intermediate parts, and adapted to stop the out-passage of the button, substantially as set forth.

52. In a button-machine, the combination with the button-receiver open to permit of 20 the out-passage of the button, of a button-stop to prevent the button from jamming at the out-passage opening, a movable piece arranged at the out-passage opening and means for transmitting movement from said piece 25 to said stop to cause the latter to assume a stopping position, substantially as set forth.

53. In a button-machine, the combination with the receiver having the marginal opening and a notched disk, of pivotal pieces 12, 30 14, one in position to engage the outpassing button and the other raised to permit an out-passage beneath, the said pieces being loosely pivoted together at their free ends, a cam operated by said pieces, a pressure-piece engaged by said cam, and a bell-crank having a stop-arm, all said parts being arranged and operating, substantially as set forth.

54. In a button-machine, the combination with the receiver having the marginal opening and a notched disk, of pivotal pieces 12, 40 14, disposed at said opening and loosely pivoted together at their free ends, a spring tending to hold said parts in normal position, a train of mechanical parts adapted to 45 be operated by the said pieces when pressed abnormally by the button to actuate a button-stop and said button-stop, all said parts being arranged and operating, substantially as set forth.

55. In a button-machine, the combination with the receiver having an opening for the button and an inclined slideway extending therefrom, of a positive button-stop disposed over said slide and at said opening, and operated by the abnormally-outpassing button 55 to prevent a passage of said button to a point of jamming, substantially as set forth.

56. In a button-machine, the combination with the receiver having an out-passage opening for the button and a slideway extending from said opening, said slideway having lugs or bearings 39, perforated to receive a removable pin to receive a pivotal cut-off or stop device having an irregularly-shaped body 65 with bent extension 41, and stopping or button-cut-off devices, and a slide 22, and means

for operating the same adapted to engage the extension and raise the cut-off and permit a passage of the button, substantially as set forth.

70

57. In a button-machine, the combination with the receiver having an out-passage opening for the button and a slideway extending from said opening, down which slideway the button may slide, of a cut-off pivoted over 75 said slideway and adapted to stay the progress of the button after it has passed through said opening, and a gate adapted to close said opening after the out-passage of the button to prevent the out-passage of a second button 80 while the first is stayed on the slideway, and means for operating said parts, substantially as set forth.

58. In a button-machine, the combination with the receiver having an out-passage opening for the button and a slideway extending from said opening, of a cut-off device pivoted above said slideway and movable toward and from the same, the button being permitted to slide between the cut-off and slideway 90 when said cut-off has moved away from said slideway, and means for throwing the cut-off away from the slideway to release the temporarily-stayed button, substantially as set forth.

95

59. In a button-machine, the combination with the receiver having an out-passage opening and a slideway extending therefrom, of a cut-off device pivoted upon said slideway, the body of said cut-off providing bearings 100 for a sliding pressure-piece and the pivot of said cut-off serving as a fulcrum for a stop-lever adapted to prevent the button from jamming at the opening, said stop-lever, and means for operating said parts, substantially as set forth.

60. In a button-machine, the combination with the receiver and slideway, staying device and a hopper receiving said button from the slideway, said hopper being adapted to 110 turn the button at right angles to the plane of movement down said slideway, and a button-carrier adapted to remove said button from the hopper, substantially as set forth.

61. In a button-machine, the combination with the receiver and slideway, staying device and a hopper at the lower end of said slideway having a valve or slide 50, normally closed by a spring and adapted to be opened by an oscillating button-carrier, and said 120 button-carrier adapted to receive the button from the hopper when said slide or valve is open, and means for operating said parts, substantially as set forth.

62. In a button-machine, the combination 125 with the receiver, notched disk and slideway, of a staying device, hopper, valve or slide for the same, oscillating carrier, rotary chuck, wheel and stripping device, and means for operating said parts, all substantially as and 130 for the purposes set forth.

63. In a button-machine, the combination

with the receiver, notched disk, slideway, means for governing the downward movement of said button over said slideway, a hopper and a valve for closing the issue-opening in 5 said hopper, of an oscillating carrier adapted to open the valve and receive the button from the hopper at one end of its oscillation and engage a chuck at the opposite end, and an oscillating and rotating chuck, and means 10 for operating all said parts, substantially as set forth.

64. In a button-machine, the combination with the receiver, notched disk, slideway, means governing the movement of the button on said slideway, a hopper valved at the lower end, a spring holding the valve normally closed, an oscillating carrier adapted to open the valve and permit a downsliding of the button, means for grasping said button on said carrier, an oscillating, rotating and longitudinally-movable chuck, a wheel, a stripping device, and operating means, all arranged and adapted to operate substantially as set forth.

65. In a button-machine, the combination with the receiver, notched and rotary disk, inclined slideway extending down from said receiver, a gate temporarily closing egress of the button from said receiver, a hopper at 15 the lower end of the slideway, a slide or valve closing the bottom of said hopper, a carrier adapted to receive the button from the hopper, and transfer it to the chuck, said chuck, a stripping device, and means for operating 20 said parts, all said parts being arranged and adapted to operate substantially as set forth.

66. In a button-machine, the combination with the receiver, notched rotary disk, inclined slideway, a gate closing egress from the receiver, a hopper receiving the button from the slideway, a valve for closing the lower end of the hopper, a spring holding said valve normally closed, a carrier oscillating back and forth from the hopper and adapted to receive 45 the button therefrom and transfer it to the chuck, said chuck, means for rotating said chuck axially, means for oscillating it to and from the carrier and means for longitudinally moving said chuck to and from the periphery 50 of the wheel, said wheel and means for releasing the button from the chuck preliminary to a return movement of said chuck to the receiver, and means for operating said parts, substantially as set forth.

67. In a button-machine, the combination with the receiver, notched rotary disk, inclined slideway, a gate closing temporarily egress of the button from said receiver, a hopper receiving the button from said slideway, the 60 said hopper having means for turning the button into a plane parallel with the plane of the fingers of the button-carrier, and a slide or valve for closing the bottom passage of the hopper and a spring for holding said 65 valve normally closed, a carrier comprising an oscillating plate, fingers adapted to be

spread apart to receive the button when the carrier engages said valve to open the same and means for closing said fingers to hold the button in the carrier after said button is 70 received from the hopper, a chuck adapted to receive the button from the carrier and present the same to a wheel and said wheel, and means for operating said parts, substantially as set forth.

68. In a button-machine, the combination with the button carrying and finishing devices, of a receiver comprising a case *d'*, the sides of which flare toward the back of the machine where it is provided with a flange, 80 which engages and is rigidly secured to an inclined rear plate, said case being open at the front, the opening being closed partly by a glass plate *d''*, and partly by a hinged door, said case at one side being open or slotted to 85 expose a portion of the notched periphery of the rotary disk, said rotary disk, and means for operating the same and for transferring the buttons from the receiver, substantially as set forth.

69. In a button-machine, the combination with the oscillating chuck, of a take-off comprising pivoted stripping-fingers 114, 114, adapted to engage the under side of the button to force the said button free from said chuck, substantially as set forth.

70. In a button-machine, the combination with the oscillating chuck, of a take-off comprising pivoted stripping-fingers, a spring tending to hold said fingers together, the said 100 fingers being adapted to enter beneath the button and force the same from the chuck, substantially as set forth.

71. In a button-machine, the combination with a chuck having pintles adapted to enter 105 the holes of the button and having a sliding collar and means operated thereby to release the pintles from holding engagement with the button, of a fixed fork 111, having curved bearings to engage the opposite sides of the 110 collar at one end thereof and cause said collar to release said button, and stripping-fingers adapted to enter beneath the button and force the same from the chuck, substantially as set forth.

72. In a button-machine, the combination with a rotary and oscillating chuck, having pintles adapted to enter the buttonholes to hold the same, said chuck being movable longitudinally in the line of the axis of rotation, 110 stripping-fingers adapted to spread apart to permit of the chuck entering between and to engage the under side of the button projecting beyond the sides of said chuck when the said chuck moves longitudinally downward 115 away from said stripping-fingers, and means for oscillating, rotating and longitudinally moving said chuck, substantially as set forth.

73. In a button-machine, the combination with a rotary, oscillating and longitudinally movable chuck and means for operating the same, said chuck having means for fixing the

button thereon, of a fixed fork having inclined bearings to engage the button-holding means to occasion a release of the button, and button-stripping fingers, all arranged and adapted to operate, substantially as set forth.

74. In a button-machine, the combination with a polishing or finishing wheel, and a rotary and oscillating chuck and means for operating the same, of an adjusting-screw and means coöoperating with the same for changing the relation of said chuck to the said wheel as the latter wears away, substantially as set forth.
75. The combination in a button-machine,

with an oscillating and rotating chuck, means 15 for oscillating the same, and a belt and pulleys for rotating said chuck, of a pair of hinged idle pulleys for said belt carried by a spring-controlled slide, substantially as and for the purposes set forth.

In testimony that I claim the foregoing I have hereunto set my hand this 27th day of June, 1898.

THOMAS F. MORRISSEY.
